UNITED STATES PATENT OFFICE.

ALEXANDER S. SPIEGEL, OF CHICAGO, ILLINOIS.

MEANS FOR HOLDING ROLLS OF MATERIAL.

1,298,811.

Specification of Letters Patent. Patented Apr. 1, 1919.

Application filed May 31, 1918. Serial No. 237,500.

To all whom it may concern:

Be it known that I, ALEXANDER S. SPIEGEL, a citizen of the United States, residing at Chicago, Illinois, have invented certain new 5 and useful Improvements in Means for Holding Rolls of Material, of which the following is a specification.

My invention relates to means for holding 10 rolls of roofing material in proper form for storage or shipment and it consists in the features and combination of parts hereinafter described and particularly pointed out in the claims.

In the accompanying drawing, Figure 1 15 represents a roll of roofing or like material with my holding means in place in connection therewith.

Fig. 2 is a face view of one of the holding 20 members or clips in the form in which it is stamped out of sheet material.

Fig. 3 is a perspective view of one of the 25 clips.

Fig. 4 is a sectional view of a portion of 30 a roll with the holder applied thereto, and, 25 Fig. 5 is a plan view of the clip and disk in proper relation for applying to the end of the roll.

In these drawings 1 indicates a roll of material such as composition roofing and 2 indicates clips or holding members which engage 35 the end portion of the roll and are held together by a wire or other suitable connection shown at 3 extending longitudinally of the roll and having its ends suitably held in connection with the holding 40 clips. These clips are preferably of triangular form having at the corners of the triangular formation points or spurs 4 formed preferably by simply turning in the ends of the metal pieces at the apexes of the triangle. 45 These prongs are adapted to fit between the layers of the roll of material and the holding member or clip is of such size that the prongs will enter between the layers of the roll a short distance in from the edge of 50 said roll. Each clip is preferably reinforced by ribs stamped therein and these ribs merge into the central reinforcement as shown at 5 and in the center of this central 55 reinforcement an opening 6 is formed to receive the connection or wire which joins the two clips together. In placing the fastening device in connection with the roll a wire having one end enlarged is threaded through the opening in one of the clips and is then thrust through the center opening

of the roll with its free end extending from the said roll and the other clip is then threaded upon this free end and with a suitable instrument, such as a pair of tweezers 60 or a specially formed tool, this free end of the wire is turned into a loop-eye or enlargement to bear upon the outer side of the clip last placed in position to hold it in engagement with end face of the roll, its prongs 65 like those of the clip first placed in position, engaging between the layers of the roll and thus aiding in maintaining the roll in its wound up condition. The center opening of the roll may be utilized to receive any desired articles which are to be shipped with the roll, such as a can of asphalt or a receptacle containing the nails which are to be used for attaching the roofing in place on the structure to be roofed. 70 75

It will be understood that the composition 80 roofing material consists of a base and a waterproof substance applied thereto, such as tar, which latter is protected by pebbles or finely divided material applied thereto. 80

It will be understood that the wire connecting the two clips is placed under tension by drawing longitudinally through the roll and while holding it in this tense condition the free end is turned or twisted to make 85 the enlargement which prevents it from pulling through the clip last applied.

In order to protect the ends of the roll or package I employ disks of card-board 7 or I may use old pieces of roofing cut into 90 circular shape and of a diameter equal to that of the ends of the roll and these pieces are placed against the ends of the roll and the metal clips are then placed in position 95 with their points 4 puncturing these disks and entering between the layers of the roll as above described so that the disks will be held in place. These disks will cover those portions of the ends of the roll which lie out beyond the edges of the metallic clips 100 and will protect them. The clips are placed in position against the ends of the roll or the disks, just mentioned, with the convex sides of the ribs and the convex sides of the raised center adjacent the roll ends so that 105 this raised center will enter the opening of the roll or will bulge inwardly the disk at its center when this is used and the inner layer of the roll will thus be supported and this in turn will support the outer layers 110 to sustain the roll in its original shape against pressure exerted from the outside

and the articles which are filled in the roll will also act to maintain the roll in its original shape. The ribs will have a gripping effect on the disks on the ends of the roll and aid in holding the roll in its original condition.

I claim:—

1. In combination with a roll of material, clips at the end faces thereof of angular 10 form presenting corner portions which are bent to form prongs which enter-between the layers of the roll and a connection between the clips extending longitudinally through the roll, substantially as described.
- 15 2. In combination with a roll of material, one piece clips of angular form bearing upon the end faces thereof and having prongs at its corners engaging between the layers of the roll, said clips having cup-shaped centers to enter the roll space and perforated substantially centrally and a connection threaded through the openings in the clips and having enlargements bearing on the outer faces of the clips to hold the 25 clips together, substantially as described.
3. In combination with a roll of material, clips at the ends thereof of angular form with point at the corners extending inwardly, said clips having ribs on their faces 30 adjacent the ends of the roll, said ribs ex-

tending from the points inwardly and means extending through the roll to hold the clips in position.

4. In combination with a roll, disks of flexible material extending over the end 35 faces of the roll, clips having points extending through the disks and into the ends of the roll and means for connecting the clips together, extending through the center of the roll, substantially as described. 40

5. In combination with a roll of material, flexible end disks applied thereto, clips having raised centers bearing upon the disks and forcing said disks partly into the roll and means for connecting said disks together, said means extending through the roll, substantially as described. 45

6. In combination with a roll, disks of angular form at the ends thereof having prongs at their corners to enter between the 50 roll layers and having depressed centers and ribs extending from the depressed centers to the prongs and means for connecting the clips together, substantially as described. 45

In testimony whereof I affix my signature. 55

ALEXANDER S. SPIEGEL.
